(57) **CLAIM**

The ornamental design for an L-shaped power connector for type A sockets, as shown and described.

DESCRIPTION

FIG. 1 is a perspective view of the L-shaped power connector for type A sockets showing our new design;

FIG. 2 is a left side view thereof, the right side being a mirror image;

FIG. 3 is a front view thereof;

FIG. 4 is a back view thereof;

FIG. 5 is a top view thereof; and,

FIG. 6 is a bottom view thereof.

In the drawings, the broken lines depict unclaimed subject matter only and form no part of the claimed design.
